UNITED STATES PATENT OFFICE.

ANTHONY HERMAN GERARD FOKKER, OF AMSTERDAM, NETHERLANDS.

BREECH LOCK FOR MACHINE GUNS.

1,426,851.

Specification of Letters Patent. Patented Aug. 22, 1922.

Application filed September 1, 1920. Serial No. 407,540.

To all whom it may concern:

Be it known that I, ANTHONY HERMAN GERARD FOKKER, a subject of the Queen of the Netherlands, residing at Amsterdam, Netherlands, have invented certain new and useful Improvements in Breech Locks for Machine Guns (for which I have filed application in Germany, No. 310,178, filed Feb. 14, 1918), of which the following is a specification.

The type of machine gun in which the breech block, the movement of which places a cartridge in position and operates the firing pin, is given a reciprocating movement by mechanical means, such as a rotating crank, instead of being returned to the cocked position by the recoil of the explosion in the gun, is well known.

The present invention is a new and useful improvement in the means of holding the breech block firmly in position while the shot is fired, by means of independent locking members which transmit the pressure acting on the breech block, when the shot is fired, directly to the frame of the gun instead of to the crank mechanism which reciprocates the breech block.

The accompanying drawing illustrates diagrammatically the construction of the gun mechanism which forms the subject of this invention.

Figs. 1 and 2 respectively show a vertical and horizontal section of the gun mechanism, and

Fig. 3 is a cross section on the line A—B Fig. 1.

The operating crank A carries, in addition to the journal by which the breech block is reciprocated through the medium of a connecting rod, a projection on each side in which a cam faced groove B is cut. This groove engages the rear ends of the locking levers C which are pivoted at F on the frame of the gun. Part of one rotation of the operating crank A moves the breech block forward to the firing position after which the remainder of the rotation causes the locking levers C by means of the grooves B to pivot by means of the shape of the grooves B into such a position that the shoulders formed on the forward ends of the locking levers C engage with the breech block D and hold it firmly in position while the shot is fired. The arrangement is such that the locking levers are subjected only

to a compression and not to a bending stress. The means by which part of the rotation of the crank brings the breech block into position and the remainder only moves the locking levers, forms the subject of my copending application for Letters Patent of the United States, Serial No. 407,539, filed September 1, 1920. The locked position is maintained until the shot has left the barrel, whereupon the locking levers are returned by the continued rotation of the crank and the shape of the grooves B to their initial position, thus releasing the breech block which is brought back to the cocking position by the continual rotation of the crank as described in application No. 407,539, above identified. To prevent the locking levers from moving by themselves or being moved by vibration, when the ends of the levers have left the groove B, small springs E hold the front ends of the levers back against the walls G of the frame of the gun. It should be noted that by means of the invention described in my copending application hereinbefore referred to, the rotation of the operating crank remains continuous and uniform throughout the operations described.

Having now particularly described and ascertained the nature of my said invention and in what manner the same is to be performed, I declare that what I claim is:

1. In a breech block mechanism for machine guns, a rotating crank operating the breech block, locking levers pivotally mounted upon the frame of the gun, actuated by the rotation of the said crank, so as to lock the breech block in position during the firing of the cartridge.

2. In a breech block mechanism for machine guns, a rotating crank having cam faced grooves, locking levers, subject to compression but not to bending stress, pivotally mounted upon the frame of the gun, engaging behind the breech block, locking same in position during the firing of the cartridge and operated by means of said cam faced grooves formed on the operating crank and positively guided thereby.

In testimony whereof I affix my signature in presence of two witnesses.

ANTHONY HERMAN GERARD FOKKER.

Witnesses:

C. PORTER,
H. G. KUYPERS.
